UNITED STATES PATENT OFFICE.

JOEL S. JUNKIN, OF KENNEDY, ALABAMA.

SAWMILL ATTACHMENT.

1,414,740.

Specification of Letters Patent. Patented May 2, 1922.

Application filed October 29, 1919. Serial No. 334,155.

To all whom it may concern:

Be it known that I, JOEL S. JUNKIN, a citizen of the United States, residing at Kennedy, Route No. 3, in the county of 5 Pickens and State of Alabama, have invented certain new and useful Improvements in Sawmill Attachments, of which the following is a specification.

This invention relates to attachments for 10 saw mills, and the object thereof is to provide a simple and efficient apparatus to be located between the carriage track and the live rollers in position for tripping the lumber from the saw on to said live rollers and 15 prevent all danger of the lumber falling and catching on the saw, thus damaging the mechanism and injuring the operator.

Another object is to provide an attachment of this character which will effect great 20 saving in time and labor and effectually prevent all possibility of accidents to both the saw and the operator.

With the foregoing and other objects in view, which will appear as the description 25 proceeds, the invention resides in the combination and arrangement of parts and in the details of construction hereinafter described and claimed, it being understood that changes in the precise embodiment of the 30 invention herein disclosed may be made within the scope of what is claimed without departing from the spirit of the invention.

In the accompanying drawings:

35 Figure 1 represents a side elevation of the attachment constituting this invention with the trips shown lowered in full lines and raised in dotted lines,

Fig. 2 is a horizontal section taken on the 40 line 2—2 of Fig. 1,

Fig. 3 is a central vertical section taken on the line 3—3 of Fig. 1,

Fig. 4 is a detail vertical section taken on the line 4—4 of Fig. 1, and

45 Fig. 5 is a detail horizontal section taken on the line 5—5 of Fig. 1.

In the embodiments illustrated, the attachment constituting this invention is shown mounted on two cross bars or bases

1 and 2. These bases 1 and 2 carry an inverted U-shaped support 3 composed of two members 4 and 5 spaced apart and bolted to said bases, each of said members having outwardly projecting laterally extending feet 6 which are secured to the bases 1 and 2. 50

A bar 7 is mounted for vertical movement between the members 4 and 5 of the support 3 and projects at its opposite ends some distance beyond the legs of said support, having fixed thereby and rising therefrom, 60 uprights 8, 9 and 10. The uprights 8 and 10 are secured to the ends of the bar 7, while the upright 9 is secured to said bar midway its length and passes upward between the two members 4 and 5 of the support 3, being held against lateral movement by bolts or rivets 12 positioned on opposite sides of said upright.

Each of these uprights 8, 9 and 10 is provided at its upper end with a loop-shaped 70 trip member 11, all of which are positioned in the same plane as is shown clearly in Fig. 1.

A bar 13 is bolted to the support 3 near its upper end as shown at 14, said bar being 75 positioned on the outer face of the member 5 of said support. This bar 13 has outwardly and upwardly inclined arms 15 and 16 which carry at their free ends laterally extending blocks riveted or otherwise secured to the inner face of said arms, said blocks being recessed on their inner faces to provide guides for the uprights 8 and 10. 80

Fixed to and rising from the bar 7 are two standards 18 and 19 spaced inwardly 85 from the uprights 8 and 10 and positioned outside the support 3. These standards are each composed of two bars 20 and 21 which straddle the bar 7 and have mounted between their upper ends, one end of levers 90 22 and 23 which are pivotally connected with said standards as is shown clearly in Fig. 1. These levers 22 and 23 are fulcrumed midway their ends on the bolts 14 which carry the bar 13. The inner ends of 95 these levers are offset laterally outward as shown at 24 and are connected by links 25 and 26 with an actuating lever 27 fulcrumed

at one end between the members 4 and 5 of the support 3 at one side thereof near its bottom. The lever 27 is offset laterally as shown at 29 opposite the upright 9 to position it properly to receive the lower ends of the links 25 and 26 and prevent their interference with the movement of said upright and also to prevent its interference with the ends of levers 22 and 23. The 10 actuating lever 27 has its free end positioned between the members 4 and 5 of the support 3 and between the bars 20 and 21 of the standard 19 and is provided at its terminal with a laterally extending pedal 15 30 which is designed to be operated by the foot of the operator.

With reference to Figure 3, it will be seen that the invention is adapted to be positioned between the carriage and the live 20 rollers so that the trips 11 may be projected upwardly to pass into the cut in the lumber formed by the saw, so that the cut slab or board may be directed onto the live rollers by the trips to prevent the cut slab 25 from falling onto the saw and damaging the same.

From the above description it will be obvious that the weight of the bar 7 and the parts carried thereby will normally hold 30 said bar in lowered position as shown in full lines in Fig. 1. When it is desired to elevate said bar to project the trip members 11 into operative position for engaging the lumber and passing it to the live rollers, all that is necessary is to depress the free end of the lever 27, preferably by placing the foot on the pedal 30. When this lever is depressed, the links 25 and 26 will be drawn downward, thereby lowering the inner ends of the levers 22 and 23 and elevating their outer 40 ends, thus causing the bar 7 to be lifted and the uprights 8, 9 and 10 carried thereby to be moved upwardly projecting their trips 11 into operative position as shown in dotted lines in Fig. 1.

The support 3 has apertures 31 extending through the leg between the members of which the lever 27 is guided to provide for the reversal of said lever when the attachment is to be used with a left hand saw, it being obvious, all that is necessary for this is to remove the fulcrum 28, turn the lever around, and position said fulcrum in the apertures 31.

55 From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that

the device shown is merely illustrative and 65 that such changes may be made as are within the scope of the claimed invention.

Having thus fully described my invention, what I claim as new and desire to secure by Letters Patent, is:—

70 1. A slab tripping mechanism comprising a support, an actuating lever fulcrumed on said support, a horizontal bar guided for vertical movement on said support, a plurality of trips mounted upon said horizontal bar to extend upwardly therefrom, levers fulcrumed intermediately of their ends on said support, standards rising from said bar to which said levers are pivoted at their outer ends, and links connecting the inner 80 ends of said levers with said actuating lever in advance of its fulcrum.

75 2. A slab tripping mechanism comprising a support, a horizontally disposed bar mounted for vertical movement in said support, uprights fixed to and rising from said bar and having trips at their upper ends, arms extending in opposite directions from said support in which said uprights are guided, a lever fulcrumed at one end on said 90 support, and a link and lever connection between said first-mentioned lever and said horizontal bar whereby the lowering of said first-mentioned lever will operate to raise said bar and position said trips in operative 95 position.

100 3. A slab tripping mechanism comprising an inverted U-shaped support composed of laterally spaced members, a horizontal bar mounted between said members for vertical movement, uprights rising from said bar and provided at their upper ends with trip members, guides for said uprights, levers fulcrumed intermediately of their ends between the members of said inverted U-shaped support, standards rising from said horizontal bar and fixed thereto, said levers being pivoted at their outer ends to said standards, a reversible actuating lever fulcrumed at one end to one leg of said support and extending between the members of the other leg whereby it is guided in its vertical movement, and links connecting the inner ends of said levers with said actuating 110 lever.

115 4. A slab tripping mechanism comprising a supporting base, an inverted U-shaped support fixed thereto and composed of laterally spaced connected members, a horizontally disposed bar mounted for vertical movement between said members, upstanding trips carried by said bar, levers fulcrumed intermediately of their ends between the members of said inverted U-shaped support at a point near its upper end, standards 120 rising from said horizontal bar to the upper ends of which the outer ends of said levers are pivotally connected, an actuating lever 125

fulcrumed at one end to one leg of said support and having an offset portion, guides for said lever, and links connecting the offset portion of said actuating lever with the inner ends of the other levers.

5. The combination with a log track and saw; of wedge means arranged along the track and projectable vertically to enter the cut in the timber made by the saw to trip the slab cut.

10. The combination with a log track and saw; of a plurality of wedges spaced longi-

tudinally of the track, a bar connecting said wedges, and lever means for moving the bar vertically to project the wedges ¹⁵ through the cut in the timber made by the saw to trip the slab cut.

In testimony whereof I affix my signature in presence of two witnesses.

JOEL S. JUNKIN.
